METHOD OF PRODUCING COLORED SMOKE

Eberhard Neukirch, Bitterfeld, Germany, assignor
to I. G. Farbenindustrie Aktiengesellschaft,
Frankfort-on-the-Main, Germany

Application October 17, 1936, Serial No. 106,261
In Germany November 6, 1935

10 Claims. (Cl. 102—1)

This invention relates to a method of and means for the production of colored smoke and more particularly to smoke-producing charges for bombs, projectiles and the like.

5 For the purpose of indicating hits during bombing practice, it has hitherto been customary to charge the bombs with fuming sulphuric acid. Such a filling, however, merely furnishes white smoke which, especially in winter, contrasts only slightly with the landscape. Moreover, fog has been produced by allowing chlorosulphonic acid to act on lime, thereby generating a dense white mist.

It has now been ascertained, in accordance 15 with the present invention, that a yellow to brown smoke is obtainable by the action of chlorosulphonic acid on chromium compounds containing chromium in the hexavalent form.

The effect of the smoke thus produced can be intensified by the use of an additional substance, such as lime, which generates smoke in conjunction with chlorosulphonic acid. The yellow or brown coloration of the smoke is due to the formation of chromyl chloride, which, although having a boiling point of 117° C., is, owing to the considerable heat generated by the reaction, volatilized when the smoke is evolved. The chromyl chloride can also be generated, in known manner, by allowing fuming sulphuric acid to act upon mixtures of calcium dichromate and common salt. The best results are obtained by using equal parts by weight of ammonium dichromate and chlorosulphonic acid, the ammonium dichromate being preferably employed 25 in the state of fine powder, thereby ensuring a more uniform evolution of the smoke. Instead of ammonium bichromate, also sodium or potassium dichromate may be employed in the mixture, in which case it is, however, advantageous 30 to add a further quantity of caustic lime—approximately equal in weight to the dichromate present and preferably in the state of fine powder—to the first-named ingredients.

45 For cement bombs, smoke charges in accordance with the invention can be made which are composed of hexavalent chromium compounds, or mixtures thereof with lime on the one part, and chlorosulphonic acid on the other; in this case, the chlorosulphonic acid should be disposed in a closed vessel, e. g. a glass tube, separate from the rest of the reaction mixture, until the reaction is to be started.

A typical example of a practice bomb, with a 55 smoke charge in accordance with the invention, is illustrated diagrammatically in the accompanying drawing, which represents a longitudinal section of such a bomb.

In said drawing, 1 denotes the cement shell having a cap 2, enclosing a chamber 3 housing a small glass tube 4 containing chlorosulphonic acid, and surrounded with the chromium compound 5, which may contain lime in admixture. 5 6 is a tail piece attached to said shell and provided with fins 7. The impact of the bomb on the target smashes the glass tube, thereby bringing the chlorosulphonic acid into reaction with the surrounding chromium compound. The 10 relative proportions of the chlorosulphonic acid and of the surrounding chromium compound may be so adjusted that a yellowish to dark brown cloud of smoke, lasting for 5 to 10 seconds, is produced. 15

I claim:

1. A method of producing colored smoke which comprises causing a chromate compound to react with chlorosulphonic acid. 20
2. A method of producing colored smoke which comprises causing ammonium dichromate to react with chlorosulphonic acid. 25
3. A method of producing colored smoke which comprises causing potassium chromate to react with chlorosulphonic acid in the presence of 25 caustic lime.
4. A smoke-producing charge for practice bombs, comprising a breakable tube containing chlorosulphonic acid, and a chromate compound adjacent said tube. 30
5. A smoke-producing charge for practice bombs, comprising a breakable tube containing chlorosulphonic acid, and a quantity of ammonium dichromate adjacent said tube. 35
6. A smoke-producing charge for practice bombs, comprising a breakable tube containing chlorosulphonic acid, and a mixture of potassium dichromate and caustic lime adjacent said tube. 40
7. A method of producing colored smoke which comprises causing a chromate compound to react with fuming sulphuric acid in the presence of a chloride compound. 45
8. A method of producing colored smoke which comprises causing calcium dichromate to react with fuming sulphuric acid in the presence of common salt. 50
9. A smoke-producing charge for practice bombs, comprising a breakable tube containing fuming sulphuric acid, and a mixture of a chromate compound and a chloride compound adjacent said tube. 55
10. A smoke-producing charge for practice bombs, comprising a breakable tube containing fuming sulphuric acid, and a mixture of calcium dichromate and common salt adjacent said tube.

EBERHARD NEUKIRCH.
